(57) **CLAIM**

The ornamental design for an occlusion training band with buckle, as shown and described.

DESCRIPTION

FIG. 1 is a front perspective view of an occlusion training band with buckle showing my new design;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines shown in the drawings are for the purpose of illustrating portions of the occlusion training band with buckle, which form no part of the claimed design.
